ANTITILTING LOCK MECHANISM FOR PIN
BALL GAMESBert E. Mills, Oak Park, Ill., assignor to Mills
Novelty Company, Chicago, Ill., a corporation of
Illinois

Application December 3, 1934, Serial No. 755,718

7 Claims. (Cl. 273—121)

This invention relates to pin ball games of the type wherein player pieces, in the form of balls, are projected over a playing board having openings formed therein for receiving the balls, and 5 more particularly to an improved locking device for preventing further play of the game in the event the operator attempts to tilt the playing board to obtain an improper or unearned score.

One of the important objects of the invention 10 is to provide in a pin ball game of the type specified a ball lifting device for raising the balls individually from a point of assembly beneath the board into position for projection over the surface thereof, and in combination therewith, 15 means operated by tilting of the playing board for locking said ball lifting means, whereby to prevent further play of the game.

A further object of the invention is to provide 20 in combination with the aforesaid anti-tilting lock mechanism, a coin-controlled mechanism for restoring the lock mechanism to inoperative position, whereby to permit further play of the game after a coin actuation of the coin-controlled mechanism.

Other objects and advantages of the invention 25 will be apparent from the following detailed description, taken in connection with the accompanying drawings, wherein I have shown the preferred form in which I have thus far contemplated applying the principles of the invention.

Referring to the drawings:

Fig. 1 is a plan view of a pin ball game apparatus having the novel anti-tilting lock mechanism embodied therein, a portion of the playing board being broken away to show the underlying structure;

Fig. 2 is a fragmentary vertical section, on an enlarged scale taken, on line 2—2 of Fig. 1, 40 the view showing the lock mechanism in the locked position;

Fig. 3 is a view similar to Fig. 2 with the locking mechanism in the unlocked position; and

Fig. 4 is a broken transverse vertical section 45 through the apparatus taken on line 4—4 of Fig. 2.

The general construction of pin ball game apparatus is well understood in the art and will, therefore, only be described in sufficient detail 50 to give a clear understanding of the manner in which the improved anti-tilting lock mechanism is used in apparatus of this character. Referring particularly to Fig. 1, the table or frame within which the playing mechanism is supported 55 consists of transverse frame members 5 and

6 which are tied together by side frame members 7 and 8. A rectangular base board 9 is secured to the lower edges of frame members 5, 6, 7 and 8 by strips 11 (Fig. 2), said strips connecting these parts to form a ridge frame unit. The top 5 of the table is closed by a glass panel 12, below which is positioned a playing board 13 having openings 14 formed therein for receiving the balls. Panel 12 and board 13 are arranged to slide as a unit longitudinally along frame members 7 and 8 whereby to give access to the operative mechanism positioned therebelow.

In the form of game shown in the drawings 10 the parts are arranged to simulate the playing of a baseball game, the balls being directed by a 15 manually operable spring held plunger 15, having an exposed finger piece 16 projecting through front frame piece 5, along a guide channel 10. From that point the balls may take any one of 20 a number of paths depending upon the force with which they are projected, and ultimately fall through the openings 14, from whence they are directed either along chutes 17 to a receptacle 18, or are directed along a chute 19 to a smaller 25 receptacle 21, the latter being separated from receptacle 18 by a partition wall 22. In this particular game the balls which are directed along chutes 17, into receptacle 18, are intended to 30 indicate "base hits", and those which are directed along chute 19, into receptacle 21, are intended to indicate "outs." A gate plate 23, supported on a rod 24 extending transversely of the machine below chutes 17 and 18, normally 35 closes an opening 25 formed in the lower front portion of the bottom wall of receptacles 18 and 21. Opening of this gate, in a manner presently to be explained, allows the balls which have 40 accumulated in receptacles 18 and 21 to roll therefrom into a downwardly inclined U-shaped channel 26, the end of which is closed by a gate lever 27, the latter being pivoted to the frame at 28 and having an arm 29 which, in the closed position shown in Fig. 2, prevents the balls from 45 rolling through the open end of said channel 26.

Referring particularly to Fig. 2, means is provided for lifting the balls individually, and in succession, from supporting channel 26 into position for actuation by projecting plunger 15. In the embodiment shown this lifting mechanism comprises an arm 31, pivotally supported at 32 50 to the frame, and a manually operable push bar 33, mounted for reciprocatory movement in frame section 5, and provided at its outer end with an exposed finger piece 34. The free end portion 35 of arm 31 is bent upwardly from the 55

main portion of said arm, the upper end thereof being provided with a laterally projecting ball lifting plate 36 which is approximately semi-circular in form, said plate being adapted to move along an arcuate channel 37 formed in frame member 7.

Assuming the ball lifting mechanism is in the lowered position shown in Fig. 3, the operator, after having preliminary actuated the coin-controlled mechanism in a manner presently to be explained, pushes inwardly on rod 33, whereupon the latter moves against a stud 38 carried on arm 31, thereby pivoting said arm in a clockwise direction viewing Fig. 3, at the same time carrying the lowermost of the balls contained in channel 26 upwardly along channel 37 until the parts assume the position shown in Fig. 2. This operation places the ball in chute 10 immediately in front of plunger 15, from which position it may be driven by the latter over the playing board. During this lifting operation gate lever 27 is swung from the open position shown in Fig. 3 to the closed position shown in Fig. 2, this movement being effected by a stud 39 projecting from arm 31, said stud engaging in a U-shaped notch 41 formed in lever 27. Movement of the lever 27 to the closed position, upon the raising of lifting arm 31, prevents the succeeding balls from rolling from assembly chute 26 until said lifting arm has been returned to the lowered position. In this return movement of arm 31, stud 39 engages in notch 41, thereby moving lever 27 from the position shown in Fig. 2 to the position shown in Fig. 3, in which position the lowermost of the balls in channel 26 is free to roll onto lifting plate 36.

In accordance with my invention, a novel form of locking mechanism is provided which is adapted, upon the tilting of the playing board, to lock ball lifting arm 31, thereby preventing further play of the game. It frequently happens that the operator after projecting a ball onto the board, will attempt to direct the ball into a particular one of the openings 14 by lifting the front end of the table and tilting the same in such a way as to cause the ball to roll into the desired opening. The mechanism which I provide for preventing further play of the game after such an unwarranted tilting of the table consists of a latch device which operates to hold the ball lifting arm 31 in the raised position, thus making it impossible to raise the balls into position for projection over the playing board.

This latch mechanism, which is best shown in Figs. 3 and 4, comprises: a lever 42, pivotally supported at 43 on a frame bracket 44; a pawl 45, pivotally supported at 46 on frame member 7; an arm 47, pivotally connected at 48 to lever 42, the opposite end thereof being adapted to engage a laterally projecting flange 49 carried by pawl 45; a lever 51, fulcrumed at 52 to a frame bracket 53, one arm 54 of said lever being positioned immediately below lever 42, and the other arm 55 thereof carrying a plate 56 to which is secured a semi-circular rim or strip 57; a second plate 58, secured to frame member 5, and having a semi-circular strip 59 secured thereto and opposing the semi-circular strip 57 carried by plate 56; and a ball 61 normally retained in the semi-circular cup formed by plate 58 and strip 59.

In Fig. 3 the anti-tilting lock mechanism is in the unlocked position, lever 51 being held in this position by a coil spring 62 which is connected at one end to a lug 63, carried by said

lever, and at the other end to a fixed point on the frame. In this position of lever 51, the tip portion 64 of pawl 45 is clear of channel 37 and affords no obstruction to the raising and lowering of ball lifting arm 31. However, as soon as the operator tilts the playing board 13 by raising the forward end of the table, ball 61 rolls from plate 58 onto plate 56, and the weight thereof immediately causes lever 51 to pivot in a clockwise direction from the position shown in Fig. 3 to the position shown in Fig. 2. Arm 54 of said lever 51 is thus raised and in turn raises lever 42 and arm 47, the latter in turn pivoting pawl 45 to the latched position shown in Fig. 2, in which position it will be noted that the point 64 thereof extends over or laps the edge of channel 37. If at this time lifting arm 31 happens to be held in the raised position, against the tension of a coil spring 65, it will be obstructed at the beginning of its downward stroke, and will be held in the locked position shown in Fig. 2. If, at the time of tilting, lifting arm 31 happens to be in the lowered position shown in Fig. 3, it may be raised to lift one more ball to projecting position. On this upward stroke lifting plate 36 brushes past the tip portion 64 of pawl 45 and on the return stroke is caught by the latter, being retained in the locked position shown in Fig. 2. This limited movement of pawl 45 and arm 47 is permitted by reason of the pivoted connection provided between arm 47 and lever 42, the latter being provided with stops 66 and 67 which limit the movement of said arm 47. A coil spring 68, extending between lever 42 and arm 47, urges the latter upwardly against stop 67. A leaf spring 69, secured to the under face of plate 56, engages a bracket arm 71 projecting downwardly from plate 58 and serves to cushion the turning of lever 51 under the weight of ball 61.

Coin-controlled mechanism is provided for restoring the anti-tilting lock mechanism to inoperative position, whereby to permit resumption of play until said mechanism is again thrown to locking position. Referring to Figs. 1 and 4, it will be noted that rod 24, which carries gate plate 23, is provided with a laterally bent or offset portion 72 which engages the lower end of an arm 73 which projects downwardly from, and forms an integral part of, lever 42. This offset portion 72 terminates in a portion 74 which forms, in effect, a continuation of rod 24, said portion 74 being positioned immediately above lever 51. The other end of rod 24 is provided with a down-turned portion 75 which is connected through a clamp 76 to a link 77, the opposite end of said link 77 being pivotally connected at 78 to the piston 79 of an air cylinder 81. A coin slide 82, supported in front wall section 5, is arranged, when pushed inwardly to the limit of its stroke, to engage a bar 83 which has pivotal and sliding connection at 84 with a supporting bracket 85, the other end of said bar 83 being pivotally connected at 86 to link 77. Continuing the reference to Figs. 1 and 4, and assuming pawl 45 is in the locked position shown in Fig. 4, after a proper coin has been placed in a slot 87 in slide 82, the latter may be pushed inwardly against the tension of a coil spring 88 through a full stroke to bring the inner end of slide 82 against bar 83. Said bar 83, together with link 77 and piston 79, are thereupon moved to the left, viewing Fig. 1, which movement, in turn rotates rod 24 in a clockwise direction viewing Fig. 1. This turning of rod 75

24 lowers gate plate 23, allowing the balls which have accumulated in receptacles 18 and 21 to roll downwardly into chute 26. This movement of rod 24 also causes the end portion 74 thereof to move downwardly onto the arm portion 54 of lever 51, causing the latter to pivot in a counter-clockwise direction, viewing Fig. 3, to bring plate 56 back to the level of plate 58, which movement returns ball 61 from the position shown in Fig. 2 to the position shown in Fig. 3. The arm 54 of lever 51, having thus been removed from lever 42, the latter is free to pivot in a counter-clockwise direction, viewing Fig. 4, to restore pawl 45 to the unlocked position shown in Fig. 3. Arm 47 normally overbalances lever 42 so that this turning of the latter occurs automatically as soon as arm 54 has been removed from its supporting position below said lever 42. As the operator releases coin slide 82, the latter is returned to normal position by spring 88, and air cylinder 81 slowly moves the parts back to normal position, this movement in the case of rod 24 consisting of a turning thereof in a counter-clockwise direction, viewing Fig. 1, to raise the arm portion 74 thereof away from tilting lever 51.

I have also shown in the accompanying drawings a ball-operated lock mechanism for throwing locking pawl 45 into locked position independently of the operation of tilting lever 51. This locking mechanism forms the subject matter of my co-pending application, Serial No. 755,717, filed of even date herewith, and will therefore be described only in a very general way. It consists of an arm 89, which forms an integral part of lever 42, and which extends through a slot 91 formed in the side wall of receptacle 21, the end of said arm carrying a lip 92 which is positioned to be engaged by a ball rolling from chute 19 into receptacle 21. The third "out" ball which enters receptacle 21 rests permanently on lip 92 thereby throwing lever 42, arm 47, and pawl 45 to the latched position shown in Fig. 2. The removal of the ball from lip 92 by the opening of gate plate 23 and the raising of arm portion 72 of rod 24 from arm 13, allows lever 42 and arm 47 to return to the unlocked position. Since this locking action occurs with the ball lifting arm 31 in the lowered position, one more ball may be raised to the playing board after the arm 31 has been thus locked. To prevent this extra ball from rolling to scoring position there is provided a lever 93, pivoted at 43 to bracket 44, and provided with an arm 94 projecting through slot 91 into receptacle 21, the end of said arm 94 being provided with a lip 95 which lies immediately adjacent the lip 92 of lever 89. A wire 96, carried by the other arm of lever 93, extends downwardly into the entrance channel of receptacle 21. Rolling of the third "out" ball into receptacle 21, as just explained, locks the ball lifting mechanism. This third ball also engages lip 95 to pivot lever 93 in a clockwise direction, viewing Fig. 4, thereby lowering wire 96 to bring the free end thereof into position for preventing the last projected ball from rolling into the portion of receptacle 18 which represents the scoring position. After the balls have been allowed to roll from receptacle 21, lever 93 is returned to non-obstructing position by a coil spring 97 which extends between said lever and a fixed point on the frame. As previously stated, the operation of the ball lifting locking mechanism through arm 89 is entirely independent of the locking thereof through anti-tilting lever 51. Although but a

single latch element is provided for locking lever 31, from either source, each locking operation is independent of the other.

The foregoing detailed description has been given for clearness of understanding only, and no unnecessary limitations should be understood therefrom, but the appended claims should be construed as broadly as permissible, in view of the prior art.

What I regard as new and desire to secure by Letters Patent is:

1. In a pin ball game, the combination with a playing board, and means for lifting the balls individually from a point of assembly beneath the board into position for projection over the surface thereof, of means operated by tilting of the playing board for locking said ball lifting means to prevent further operation thereof, and coin-controlled mechanism for restoring said locking means to inoperative position, whereby to permit resumption of play after a coin actuation of said coin-controlled mechanism.

2. In a pin ball game, the combination of a playing board, a vertically oscillating ball lifting device for elevating the balls individually from a point of assembly beneath the board into position for projection over the surface thereof, a locking element arranged for movement into position obstructing operation of said lifting device, means operated by tilting of the playing board for moving said element to locking position, and coin-controlled mechanism for restoring said locking element to inoperative position, whereby to permit resumption of play after a coin actuation of said coin-controlled mechanism.

3. In a pin ball game, the combination of a playing board, a vertically oscillating ball lifting device for elevating the balls individually from a point of assembly beneath the board into position for projection over the surface thereof, a latch arm for holding said lifting device against movement through the return stroke thereof, means operated by tilting of the playing board for moving said arm to latched position, and coin-controlled mechanism for restoring said latch arm to inoperative position, whereby to permit resumption of play after a coin actuation of said coin-controlled mechanism.

4. In a pin ball game, the combination with a playing board, and means for lifting the balls individually from a point of assembly beneath the board into position for projection over the surface thereof, of means operated by tilting of the playing board for locking said ball lifting means to prevent further operation thereof, and coin-controlled mechanism for restoring said locking means to inoperative position, whereby to permit resumption of play after a coin actuation of said coin-controlled mechanism, said locking means including a latch element, a lever operatively connected therewith, a movable counterweight and a support therefor positioned adjacent said lever, said counterweight being adapted upon tilting of the playing board, to move from said support onto said lever, thereby overbalancing the latter and moving said element to latched position.

5. In a pin ball game, the combination of a playing board, a vertically oscillating ball lifting device for lifting the balls individually from a point of assembly beneath the board into position for projection over the surface thereof, a locking element arranged for movement into position obstructing operation of said lifting de-

- vice, a lever operatively connected with said locking element, means operated by tilting of the playing board for overbalancing said lever, whereby to move said element to locked position, and coin-controlled mechanism for returning said lever and locking element to inoperative position, whereby to permit resumption of play after a coin actuation of said coin-controlled mechanism.
10. 6. In a pin ball game, the combination of a playing board, means for supporting a supply of the balls beneath the board, a vertically oscillating ball lifting device for lifting the balls individually from said support to the playing board, a latch element arranged for movement into position obstructing operation of said lifting device, a lever operatively connected with said latch element, a movable counterweight and a support therefor positioned adjacent said lever, said counterweight being adapted, upon
15. 15.

tilting of the playing board, to move from said support onto said lever, thereby overbalancing the latter and moving said element to latched position, and coin-controlled mechanism for returning said counterweight and latch element to inoperative position, whereby to permit resumption of play after a coin actuation of said coin-controlled mechanism.

7. In a pin ball game, the combination with a playing board and means for moving the balls into position for projection over the surface thereof, of means operated by tilting of the board for locking said ball moving means to prevent further operation thereof, and coin-controlled mechanism for returning said locking means to inoperative position, whereby to permit resumption of play after a coin-actuation of said coin-controlled mechanism.

BERT E. MILLS. 20
